LEATHER SANDING MACHINE

Harold Thede, Sheboygan, Wis., assignor to
Armour and Company, Chicago, Ill., a corpora-
tion of Illinois

Application February 2, 1949, Serial No. 74,194

2 Claims. (Cl. 51—78)

1

This invention relates to a leather treating machine and method. The invention is particularly useful in the shaving and buffing of leather through a rotary cylinder equipped with an abrasive sheet.

In the present practice for shaving and buffing leather, an abrasive sheet is wound about a cylinder and the cylinder is brought into contact with leather for finishing the surface, small air jets being directed against the abrasive sheet to remove leather fragments collected thereon and which tend to reduce the effectiveness of the abrasive. The air jets tend to produce a channel effect and a bunching of the fragments at certain portions on the surface so that the sheet when brought into contact with a fresh portion of the leather presents an irregular surface thereto. Further, such results tend to reduce the life of the paper abrasive sheet.

An object of the present invention is to provide a new means and method for treating the paper for the removal of leather fragments, etc., whereby the life of the paper is increased and more effective abrasion of the leather surface is brought about. Yet another object is to provide a machine and method whereby a flat curtain or sheet of air is directed against the paper on the cylinder to eliminate channeling while at the same time effectively clearing the surface of the paper of fragments. A still further object is to provide an air-delivering conduit with means whereby a flat and substantially continuous air sheet or curtain is impinged upon a rotating cylinder bearing an adhesive sheet for increasing the effectiveness of the abrasive sheet while greatly increasing its effective life. Other specific objects and advantages will appear as the specification proceeds.

The invention is shown in an illustrated embodiment, by the accompanying drawing, in which—

Figure 1 is a broken perspective view of a machine embodying my invention; Fig. 2, a schematic view in side elevation showing the arrangement of the main operating parts; Fig. 3, a broken view in side elevation of the air pipe or conduit equipped with slotted nozzles; Fig. 4, a plan view of the structure shown in Fig. 3, with a portion of the pipe shown in horizontal section; and Fig. 5, a plan view of the air jet tube or pipe and its actuating arm.

The apparatus for abrading leather in which an abrasive sheet-covered cylinder is employed is well known in the art and a detailed description is believed unnecessary. In the illustration given,

10 designates a frame in which a trunnion-equipped cylinder 11 is mounted for rotation. The shaft of the cylinder is shown equipped with a pulley wheel 12 driven by a belt 13. It will be understood that any means for rotating the cylinder may be employed. The frame 10 also provides a platform 14 for receiving the leather piece 15 to be treated. Supported in the frame is a steel roller 16, and therebelow a resilient roller 17 formed of rubber or other suitable material.

At the rear of the machine, the leather piece may be fed out of the machine above the cross girt 18 or, if desired, below the cross girt.

At the rear of the machine is an air jet tube 18 mounted for reciprocation in guides 19, and the tube is equipped with an actuating arm 20.

The actuating arm 20 is provided with an inverted end portion received within a spiral slot 21 of a rotatably-mounted cam member 22. The

cam member is equipped with a shaft carrying a pulley 23 driven by a belt 24 also engaging a pulley carried upon the shaft of cylinder 11.

The tube or pipe 18 is provided throughout its length with spaced threaded openings into which are secured threaded nozzles 25. The nozzles are provided with an air passage 26, and the outer end of the nozzle is provided with a narrow transverse slot 27, as shown more clearly in Figs. 3 and 4. The nozzles are arranged so that the transverse slots 27 are aligned, as indicated in Fig. 3, and each of the nozzles delivers a flat fan-shaped stream, as indicated best in Figs. 2 and 5. The fan-shaped flat streams preferably overlap as they strike the abrasive-covered sheet of the cylinder and form a substantially continuous flat curtain or sheet of air extending across the face of the abrasive sheet 28.

The abrasive sheet may be of any type or structure. Ordinarily, the abrasive sheet consists of paper having abrasive material bonded thereto and it is wound around the cylinder and locked thereto by movable clamps (not shown).

Compressed air or other gas may be supplied to the reciprocating tube 18 by any suitable means. In the specific illustration given, a flexible air tube 29 is connected to the tube 18 at 30 and the tube 29 leads to a compressed air reservoir or to any other source.

Operation

In the operation of the machine, the leather piece 15 is fed forwardly over the platform 14 and between the steel roller 16 and the rubber or resilient roller 17. The more rapidly driven cylinder 11 carrying a sheet 28 of abrasive, shaves

and buffs the leather surface and the leather piece is removed at the rear end of the machine, as is illustrated in Figs. 1 and 2. The tube 12, with its slotted nozzles, delivers a flat curtain or sheet of air in a substantially continuous phase across the front of the cylinder just above the leather piece 15. The curtain or sheet of air causes the fragments of leather, etc. on the abrasive sheet 28 to fall upon the leather piece 15 that is being removed below and the cleaned sheet of abrasive is rendered effective for engagement with a new surface of the leather piece.

While employing no more air than has heretofore been employed in the air jet pipe and other conditions remaining the same, I find that the flat sheet or curtain of air produced by the combined slotted nozzles eliminates channeling while at the same time greatly increasing the life of the abrasive sheet. At the same time, the abrasive sheet, by virtue of the uniform removal of leather fragments therefrom, is much more effective in the abrading operation.

For example, in the use of standard apparatus, it is common to get sand paper scratches or lines on the leather and if these are excessive in number or too deep, it is necessary to re-buff the leather. With the new structure, there are fewer of such "sand paper scratches or lines" and re-buffing is not necessary.

In tests made with the prior type of machine in which ordinary air jets were discharged against the sand paper, and with the new machine in which slotted nozzles were employed, it was found that with the standard machine employing the perforated pipe, 83 sand paper sheets were employed for buffing 10,277 leather sides, while with the new machine employing the fan jet or slotted nozzle structure 11,664 sides were buffed while using only 58 sheets. It will thus be seen that the new machine almost doubled the life of the abrasive sheets.

In another test the old machine with the perforated pipe buffed 11,664 sides using 94 abrasive sheets while the new machine with the fan jet buffed 11,664 sides using only 58 sheets. Over a series of tests, it was found that the old machine with the perforated pipe buffed 123 sides per sheet while the new machine employing the fan jet air pipe buffed 201 sides per sheet. The savings in one small plant using seven machines was \$259.55 per week, or \$12,978.00 per year.

Why the above surprising result is achieved, I am not fully able to explain. It may be that the

jets heretofore employed produced eddying, causing the fragments to be rearranged upon the abrasive sheet surface with channel effects, while the flat stream, in addition to removing the fragments, serves as a barrier to prevent return of the fragments to portions of the surface. In any event, the use of the same amount of compressed air in the flat sheet or curtain-like arrangement described not only eliminates channeling and presents a uniformly cleaned abrasive sheet for engagement with new leather surfaces, but also the effective life of the abrasive sheet is almost doubled.

While in the foregoing specification, I have set forth a single embodiment in considerable detail for the purpose of illustrating the invention, it will be understood that such details of structure may be varied widely by those skilled in the art without departing from the spirit of my invention.

I claim:

1. In a leather-treating machine having a driven cylinder equipped with an abrasive sheet and a resilient roll for urging a leather strip against said abrasive sheet, an air jet pipe mounted for reciprocation in front of said cylinder and provided with spaced openings, means for reciprocating said pipe, and slotted means associated with said pipe opening for directing horizontally-aligned fan-shaped streams of air toward the abrasive sheet of said cylinder.
2. In a process for abrading leather in which an abrasive sheet-covered cylinder is rotated against the leather to be treated, the steps of impinging against the abrasive sheet surface on the cylinder a flat substantially-continuous curtain of air extending longitudinally of the cylinder, and reciprocating said curtain longitudinally of the cylinder.

HAROLD THEDE.
